UNITED STATES PATENT OFFICE.

ALLAN E. FRANCIS, OF CLEVELAND, OHIO.

COUNTER-SEAT.

SPECIFICATION forming part of Letters Patent No. 297,982, dated May 6, 1884.

Application filed May 5, 1883. (No model.)

To all whom it may concern:

Be it known that I, A. E. FRANCIS, a citizen of the United States, residing at Cleveland, in the county of Cuyahoga and State of Ohio, have invented a new and useful Counter-Seat for Stores, of which the following is a specification.

The object of this invention is to provide a folding counter-seat that can be secured to the floor of the room without depending upon the counter for fastenings or supports, and be so constructed as to be conveniently and compactly closed up in front of the counter, and be opened or closed by a person when either in front or back of the counter. In this class of counter-seats, including folding seats generally, and of which Letters Patent of the United States No. 240,117 forms a feature, attachment has been made entirely to the counter, making it necessary that in construction the counter should be especially adapted to the purpose to insure firm fastenings for the seat, and also to resist the pressure tending to overturn it by the weight of a number of persons seated on such seats attached thereto. The great variety of designs in counter-fronts, as well as the difference in strength and security of the parts to which such seats must be affixed, renders the object sufficiently plain.

In the accompanying drawings, Figure 1 is a side elevation, showing the seat extended for use as operated by the trip, shown under the counter. Fig. 2 is the same closed up, with trip shown in dotted lines. Fig. 3 is a front elevation of the seat extended for use, shown at end of counter. Fig. 4 is a section of top of seat. Fig. 5 is an under side view of top of seat. Fig. 6 is a front view of trip for tilting seat.

The seat consists, essentially, of top A, leg L, supports o o, with support s', which, when combined and secured to the floor at d, form a substantial counter-seat.

The seat-top of support L is a suitable top for the fastenings, and consists, preferably, of a circle of wood, c, forming the frame for the cane or perforated-wood seat e, which is mounted on metal spider b, provided with ears

t t and y y, for hinging of supports o o and leg L, respectively.

The supports o o may be made of wood or metal, the latter solid or in pipe or tubing, screwed, pinned, or riveted in the hollow metal end pieces, which form a part of the joints upon which the seat is tilted.

The supports o o are provided with sleeves n n, to which the support s' is attached.

Leg L may be constructed of wood and metal, or either alone, but preferably with the upper end of metal, and forked for accommodation of the folding arrangement, which consists of arm s, hinged at h, extending to f, and being connected to the seat by link v, and to the floor by rod r, and to the slide on leg L by a hinge, so that when the seat is moved, as in the act of closing, rod r moves arm s forward, throwing support s' back, tipping top A down, and bringing all into the position shown by Fig. 2, which can be done either by the hand applied to the seat or by applying the foot to the trip m and closing it by the folding arrangement, which consists of adjustable rod k, hinged to lower part of support o, and of trip m, to which the other end of rod k is hinged, the trip m being made of metal and provided with two leaves placed in suitable positions for applying the foot, one to trip and extend the seat, and the other to close the seat by pressure, as shown by the drawings.

What I claim, and desire to secure by Letters Patent of the United States, is—

1. The combination, with the seat-top, of support L, hinged thereto, the supports o o, hinged to the seat-top, and provided at their lower end with means whereby they may be hinged to the floor, arm s, connected to the supports L and o o, substantially as described, and link v, connecting the upper end of arm s and the seat-top, as and for the purpose specified.

2. The combination, with the seat-top, of support L, hinged to the same, bracket d, supports o o, hinged to the seat-top and bracket d, arm s, connected to the supports L and o o, substantially as described, link v, connecting the upper end of arm s with the seat-top, and

rod *r*, connected to arm *s*, as set forth, and pivoted to bracket *d*, as and for the purpose specified.

3. The combination, with the seat-top, of support *L*, hinged to the same, bracket *d*, supports *o o*, hinged to the seat-top and to bracket *d*, arm *s*, connected to supports *L* and *o o*, substantially as set forth, link *v*, connecting the upper end of arm *s* with the seat-top, rod

r, connected, substantially as described, with rod *r*, connected to arm *s*, and hinged to the bracket *d*, the treadle *m*, and rod *k*, connecting the same to supports *o o*, as and for the purpose specified.

ALLAN E. FRANCIS.
